UNITED STATES PATENT OFFICE.

WILLIAM DOCKRAY RATCLIFFE, OF LIMEHOUSE, LONDON, ENGLAND, ASSIGNEE TO THE CROSS-RATCLIFF LINING AND MOUNTING MACHINERY COMPANY, LIMITED, OF LONDON, ENGLAND.

MACHINE FOR AFFIXING SHEETS OF PAPER OR THE LIKE TO BOARDS, CARDS, OR LIKE MOUNTS.

Application filed May 24, 1926, Serial No. 111,301, and in Great Britain January 16, 1926.

This invention relates to improvements in machines for affixing sheets of paper or the like to boards, cards or like mounts, and has for its primary object to so construct the machine that the said sheets of paper or the like will remain undistorted during the process of applying the adhesive, and also during mounting and finally pressing.

In the machine constructed according to my invention the said sheet or sheets of paper or the like is or are retained in a flat horizontal plane throughout the whole process and is thus unsubjected to stress or warping. Further, during the application of the adhesive to its face, the said paper or the like is held stationary in a flat plate, the said adhesive being applied by a system of rollers adapted to travel in a horizontal plane parallel to the face of the paper.

I provide travelling pasting rollers which are caused by my construction to lift from the paper during the forward movement and are lowered into contact therewith during the backward and operative stroke.

I employ a continuous belt, and a mounting roller which remain stationary during half a cycle of operations of the machine, the latter making a complete revolution during the other half cycle of the machine.

And in order that my invention may be completely understood, reference should be made to the accompanying sheets of drawings:

Fig. 1 is a general arrangement in part sectional elevation of the complete machine, the upper portion of the side frame member being removed.

Fig. 2 is a plan view of the machine.

Fig. 3 shows to a larger scale in detail the system of travelling rollers for applying the adhesive, such as mucilage, paste, glue or the like, to the sheets.

Fig. 4 is a part transverse sectional elevation, to a larger scale, of the travelling rollers shown in Fig. 3.

Fig. 5 is a sectional elevation to a larger scale of the roller which applies the adhesive to the paper.

Fig. 6 is a section of one of the distance pieces at the ends of the adhesive applying roller.

Fig. 7 is a detail section through the upper mounting roller.

Fig. 8 is an end view of the machine.

Fig. 9 is a detail of the driving mechanism of the mounting rollers.

Fig. 10 is a detail of the mechanism for reciprocating the travelling rollers which apply the adhesive.

Fig. 11 is a detail of the cam mechanism for operating the feed lays or stops for the paper, the lifting mechanism of the travelling rollers, and for controlling the negative air pressure to the under-side and leading edge of the said paper or the like.

Fig. 12 is a detail of the cam mechanism for controlling the lays or stops for the boards or like mounts.

Referring to Figs. 1 and 2, transversely arranged between the side frame members 1 and 2 of the machine and mounted in suitable bearings thereon, are the feed rollers 5 and 6 for conveying the sheet of paper or the like from the feed board, the mounting rollers 7 and 8 which apply the said paper to board or like mount after the application of the adhesive, and the pressure rollers 9 and 10 which serve to exert pressure between the said paper and the mount and so cause more complete adhesion.

The feed rollers 5 and 6, arranged one above the other, are mounted on transverse shafts 5^A and 6^A suitably and rotatively mounted in bearings in the side frame members 1 and 2 and provided with spur gears 5^B and 6^B, adapted to mesh one with the other.

The mounting rollers 7 and 8 are similarly arranged on shafts 7^A and 8^A which are rotatably mounted in adjustable and spring-pressed bearings or plumber blocks 15 and 16 secured to the said side frames 1 and 2, and are provided with intermeshing gear wheels 7^B and 8^B.

The transverse shafts 9^A and 10^A of the rollers 9 and 10 are similarly mounted in spring-pressed and adjustable bearing or plumber blocks 17 and 18 and have secured thereto intermeshing spur gears 9^B and 10^B.

A continuous conveyor belt 12 which may be formed of webbing, canvas or other suitable material, is adapted to pass over the

lower feed roller 6 and the lower mounting roller 8 in such manner that the paper or the like to be mounted, will be conveyed from the laying-up or feed table 11 over a fixed plate 22, to the mounting rollers 7 and 8.

Tapes 23, adapted to pass over small transverse rollers 24 and 25, serve to convey the board or like mount after the paper or the like has been mounted thereon, from the mounting rollers 7 and 8 to the pressure rollers 9 and 10. The said roller 25 is driven through the medium of spur wheels 26 and 27 from the gear wheel 28 mounted upon the shaft 10^A of the lower compression roller 10 (see Figs. 2 and 8).

Mounted upon and suitably secured to the upper face of the side frame members 1 and 2 and arranged in alignment therewith at the feed end of the machine, are sub-frame members 19 and 20 each formed with a parallel and horizontal slideway or channel 21. Within the longitudinal channels 21 are adapted to slide blocks 30 (see Fig. 4) rotatably mounted at the extremities of a transverse shaft 31. The said transverse shaft 31 has mounted thereon a roller 32 which is adapted to contact with a parallel roller 33 mounted in adjustable bearings 34 (see Fig. 3) in end plates 35. Beneath the said roller 33 and contacting therewith is a sectional roller 37 mounted in adjustable bearings 36 in the end plates 35. The rollers 33 and 37 are driven by the shaft 31 through the medium of spur gears 38, 39 and 40 (see Fig. 3) mounted upon the shafts 31, 33^A and 37^A of the said rollers 32, 33 and 37 respectively. The roller 32 is adapted to rotate in a trough 50 containing the adhesive paste, mucilage, glue or the like, in such manner that on the rotation of the said roller 32, a thin film of the said adhesive will be evenly distributed over the face of the said sectional distributing roller 37, through the medium of the intermediary roller 33, for application to the upper surface of the sheet to be mounted.

Loosely mounted upon the shaft 31, near its outer extremities, are spur pinions 41 which mesh with parallel racks 42 secured to the sub-frame members 19 and 20, in such manner that on the shaft 31, carrying the system of rollers applying the adhesive, being moved laterally in the slideways 21, the said spur pinions 41 will be rotated. These loosely mounted pinions 41 are provided with spring controlled pawls 43 (see Fig. 3) which are adapted to engage ratchet wheels 44 rigidly secured to the shaft 31 in such manner that the said pawls 43, will only engage the said ratchet wheels 44 when the shaft 31 is moved laterally from the centre towards the feed end of the machine. Thus the system of rollers 32, 33, and 37 will be

rotated during this lateral backward movement and will remain stationary during the forward movement of the travelling shaft 31. The said shaft 31 has rotatively mounted thereon at either end, adjacent the ratchet wheels 44, links or rods 61 and 62 which form an operative connection with crank arms 63 and 64 secured to the transverse shaft 65 (see Fig. 10). Secured to the shaft 65 is a spur pinion 66 adapted to engage a rack 67 of a rocking quadrant 68. The said quadrant is pivotally mounted on a shaft 69 and is connected at its lower extremity by means of a link 70 with a crank pin 71 secured in the end disc 72 of the cross driving shaft 57. On the rotation of the said shaft 57 the spur pinion will be given a partial rotation alternatively in either direction, causing the travelling rollers to move backwards and forwards over the face of the conveyor belt 12.

Above the distributing roller 33 and secured to the end plates 35 and 36 is a transverse shaft 51 extending across the breadth of the machine and provided at its outer ends with small rollers 52 and 53. These said rollers 52 and 53 are adapted to rest upon horizontal shafts 54 and 55 eccentrically mounted in recesses in the upper face of the sub-frame members 19 and 20 in such manner that on the said horizontal shafts 54 and 55 being given a partial rotation the transverse shaft 51 will be given a slight vertical movement which will result in the distributing roller 37 being lifted from the face of the paper. The eccentric shafts 54 and 55 are operated by means of a cam 56 (see Fig. 11) mounted upon the transverse driving shaft 57 through the medium of levers 58, links 59, transverse rocking shaft 60, vertical connecting rod 61 and the bell crank cam lever 62. The said cam 56 is so designed and positioned on the said shaft 57 that the said eccentric shafts 54 and 55 will be given a partial rotation and cause the distributing rollers 37 to be lifted during the forward movement of the adhesive applying rollers.

The said distributing roller 37 is constructed from a multiplicity of short rollers or sections 37^B (see Fig. 5) all ground to the same diameter and mounted upon the central shaft 37^A. Distance pieces 37^D of reduced diameter are provided at each end to bring the overall length of the roller up to the normal dimensions between the bearings. Fig. 6 shows a section of such distance piece 37^D which is tapped at its central line to screw upon the threaded portion of the shaft. By using various numbers of sections and lengths of distance pieces the length of the adhesive applying roller 37 may be accurately adjusted to the exact width of the paper or the like to be mount-

ed, thus ensuring that no adhesive is applied to the belt 12 and dispensing with the use of blankets or like devices.

With reference to Fig. 9, loosely mounted upon the shaft 8^A of the lower mounting roller 8 is a spur pinion 72 adapted to engage a rack 73 formed on the face of a quadrant 74. The said quadrant 74 is pivotally mounted on a shaft 75 and is connected 10 at its lower end or opposite arm 76 by means of a link 77 with a crank pin 78 secured between the two main driving wheels 79 and 80, mounted upon the transverse shaft 57. The driving wheels 79 and 80 have gear teeth formed on their peripheries which mesh with the spur pinions 83 and 84 mounted upon the main transverse driving shaft 85. The main driving shaft 85 is adapted to pass through suitable bearings 20 in the side frame members 1 and 2 and carry on one side a driving pulley 86. On the opposite side of the machine the projection of the shaft 85 carries a small pulley 87 for the purpose of driving the pressure rollers 25 9 and 10 through the medium of a driving belt 88 and spur wheels 89 and 90 suitably mounted on shafts 89^A and 90^A.

On the rotation of the driving shaft 85 and the wheels 79 and 80 the quadrant 74 (see Fig. 9) is oscillated or given a partial rotation alternatively in either direction. The spur pinion 72 is rigidly secured to a ratchet 81 which is adapted to engage a spring-pressed pawl 82 pivotally mounted 35 upon the spur wheel 8^B of the lower mounting roller 8. The quadrant rack and pinion 73 and 72 with the pawl 82 and ratchet disc 81 are so arranged that the roller 8 will be given a complete revolution in one 40 direction during one half of a revolution of the driving wheels 79 and 80 and will remain stationary during the other half of the revolution of the said driving wheels.

Thus the upper part of the conveying belt 45 12 will move forward during the first half of each cycle of operations and will remain stationary throughout the remaining period of such cycle.

Referring to Fig. 7, the upper mounting roller 7 is of segmental form, the cut-away portion 7^C of which is presented to the lower roller 8 during the stationary period of the cycle of operations, in order that the mounts may be fed from the inclined board 55 91 up to the lays or stops 92. The said lays or stops 92 are carried on a transverse member 93 and are formed with longitudinal slots 92^A (see Fig. 2) along their length in order that the position of the said lays 60 may be adjusted according to the position on the said board or mount to which it is desired to affix the said sheet of paper or the like.

The said transverse member 93 is secured 65 at either end to arms or levers 94 pivotally

mounted at their lower ends on a shaft 95 which is operatively connected with a cam 99 secured to the driving shaft 57 by means of a lever 96, a link 97, and a cam lever 98. The cam 99 is so designed that the lays 92 70 are drawn backwards out of their operative position shortly after the rollers 7 and 8 commence to rotate.

In order that the leading edge of the sheet of paper or the like may be held securely 75 to the face of the conveyor belt 12 during the process of applying the adhesive, the plate 22 is provided across its face at a point where the said leading edge of the paper normally comes to rest, with a series 80 of holes 100 connected by means of a pipe 101 to a small air vacuum pump 102. This vacuum pump 102 is driven by means of a belt 103 from a pulley 104 mounted upon the driving shaft 57. A release valve 105 is 85 provided in the pipe 101 and operated by means of a link 106 connected to the cam lever 62 in such manner that negative pressure will be exerted on the underside of the conveyor belt 12 during the process of applying the adhesive to the paper or the like and will be released during the forward movement of the said belt.

The said cam lever 62 is also operatively connected by means of the links and levers 107, 108, 109, 110, 111, and 112 with the transverse rod 113, carrying the feed lays or stops 114 of the feed board 11 for the said paper or the like. The said rod 113 is carried in end bearings in the brackets 123, supporting the feed board 11 and secured to the end frame member 3. Swinging brackets 115 and 116 (see Figs. 2, 3 and 4), are rotatively mounted upon the shaft 5^A and carry a feed roller 117 mounted in suitable bearings between them. The said feed roller 117 is driven from the shaft 5^A by the chain of gears 118, 119, 120 (see Fig. 3) and is adapted to contact with a complementary roller 121 mounted beneath it in 110 suitable bearings carried by the brackets 123.

Suitably mounted between the side frame members 1 and 2 and located beneath the upper portion of the belt 12 between the plate 22 and the system of mounting rollers 115 7 and 8 is a gas heater 122 for the purpose of applying heat to the paper and the like after the application of the adhesive in order that any superfluous moisture contained in the said adhesive may be 120 evaporated before the said paper or the like is applied to the said board or mount.

The cycle of operation of the machine is as follows:—The machine commences operation in the position shown in Fig. 1, the 125 paper or the like to be mounted having been fed up on the board 11 by the rollers 117 and 121 to the lays or stops 114. The pawl 82 mounted upon the spur wheel 8^B of the roller 8 is now in engagement with the 130

ratchet face of the disc 81 and on the rotation of the main driving pulley 86, the quadrant 74 will move in an anti-clockwise direction causing the rollers 7 and 8 to move through a complete revolution. The conveying belt 12 will thus move forward rotating the feed rollers 5 and 6. At the same time the cam 56 will operate the lays or stops 114 causing them to fall away out of engagement with the leading edge of the paper. The said paper or the like is then free to be moved forward by the rollers 117 and 121 into contact with the feed rollers 5 and 6. The belt 12 thus conveys the paper or the like over the plate 22 until the leading edge of the said paper just passes the suction holes 100 in the said plate. The rollers 7 and 8 having completed a revolution will then cease rotation and the belt 12 will remain stationary during the next half of the cycle. The cam 56 now operates the valve 105 and causes negative pressure to be applied to the holes whereby the said leading edge of the said paper will be caused to hold tightly to the belt 12 and so be securely fixed in position. Meanwhile the system of rollers 32, 33, and 37, for applying the adhesive, have been moved forward over the said paper by the quadrant 68, the roller 37 during this motion having been lifted from contact with the surface of the said paper by the combined actions of the cam 56 and the eccentric shafts 54 and 55. Further, during this forward movement, the pawls 43 mounted on the gear wheels 41 have not engaged the ratchet wheels 44 with the result that the rollers 32, 33, and 37 have remained stationary.

On reaching the limit of its forward movement the cam 56 and the eccentric shafts 54 and 55 allow the roller 37 to make contact with the said paper and remain in such contact during the backward motion of the said travelling roller system. The spur wheels 41 being reversed by the racks 42, the pawls 43 now engage the ratchet wheels 44 and cause the rollers 32, 33 and 37 to rotate, thereby distributing a thin film of adhesive to the upper surface of the said paper.

During this process the said paper is held to the surface of the fabric belt 12 by the suction exerted by the vacuum pump 102.

On the system of travelling rollers reaching the backward limit of its movement, the suction on the belt 12 is released in the manner previously described and the said fabric belt is again moved forward by the roller 8 conveying the adhesive-treated paper over the heated chamber 122 where it again pauses during half a cycle of the operation for the purpose of extracting superfluous moisture from the said adhesive. The board or mount upon which the paper is to be affixed is now fed down the inclined board 91 against the lays or stops 92. On the fur-

ther movement of the rollers 7 and 8 and the fabric belt 12, the lays or stops 92 are withdrawn in the manner before described and the said paper is conveyed into contact with the said boards or mounts and pressed 70 into position thereon by the said rollers 7 and 8.

After passing the said rollers 7 and 8 the board or mount with the paper affixed thereon is conveyed by the tapes 23 to the pressure rollers 9 and 10 which exert a final pressure on the said mount and paper, to cause a more complete adhesion.

From the above it will be observed that throughout the process, the said paper or 80 the like is maintained in a flat horizontal position, and cannot be subjected to undue strain or warping. Further, the roller applying the adhesive to the said paper being positively rotated through the chain of gears 85 38, 39, 40 and 41, by the fixed racks 42, secured to the side frames, describes a true rolling motion without "drag" over the face of the said paper, thereby applying an even 90 coat of adhesive to the surface of the said paper.

It will be observed that by adjusting the position of the stops 92 and laying the board up to them, a sheet of a very small size may be mounted on a board in any position with 95 relation thereto however large the board may be within suitable limits up to the size the machine will take. The paper is placed always in the same position.

As compared with usual practice in machines of this kind which generally comprise 100 means for passing the paper to be mounted round a roller during the pasting process, during which process the paper may therefore suffer distortion or even occasional folding, the method according to the present invention, by keeping the paper in a flat horizontal plane and keeping it also stationary when the paste is applied, serves to prevent 105 any distortion or warping of the paper. 110

What I do claim as my invention and desire to secure by Letters Patent is—

1. In a machine of the character described for affixing sheets of paper or the like to mounts, a member over which the mounts are 115 fed, means for feeding the sheets of paper through the machine and into position to be affixed to the mount, and reciprocating means for applying an adhesive to the sheet, said reciprocating means being out of engagement with the sheet when moved in one direction but engaged with the sheet when moved in the opposite direction.

2. In a machine of the character described for affixing sheets of paper or the like to 125 mounts, a member over which the mounts are fed, means for feeding the sheets of paper through the machine and into position to be affixed to the mounts, and reciprocating means for applying an adhesive to the paper, 130

said reciprocating means being raised out of engagement with the paper upon movement in one direction but lowered into engagement with the paper upon movement in 5 the opposite direction.

3. In a machine of the character described for affixing sheets of paper or the like to mounts, a member over which the mounts are fed, means for feeding the sheets of paper 10 through the machine and into position to be affixed to the mounts, means for applying an adhesive to the sheets of paper, means for drying the adhesive, and means for pressing the paper onto the mount.

15 4. In a machine of the character described for affixing sheets of paper or the like to mounts, a member over which the mounts are fed, means for feeding the sheets of paper through the machine and into position to 20 be affixed to the mounts, means for applying an adhesive to the sheets of paper, means for drying the adhesive, and rollers for pressing the paper onto the mount.

5. In a machine of the character described for affixing sheets of paper or the like to mounts, a member over which the mounts are fed, means for feeding the paper through the machine and into position to be affixed to the mount, means for applying an 25 adhesive to the sheet of paper, means for holding the paper stationary while the adhesive is being applied, means for drying the adhesive, and means for pressing the paper into engagement with the mount.

30 6. In a machine of the character described for affixing sheets of paper or the like to mounts, a member over which the mounts are fed, means for feeding the sheets of paper through the machine in a flat horizontal 35 plane and into position to be affixed to the mounts, means for applying an adhesive to the sheet of paper, means for holding the paper stationary while the adhesive is being applied, means for drying the adhesive, and 40 means for pressing the paper into engagement with the mount.

7. In a machine of the character described for affixing sheets of paper or the like to mounts, a member over which the mounts are fed, means for feeding the sheets of paper through the machine and into position to be affixed to the mounts, reciprocating 45 pasting rollers for applying an adhesive to

the sheets of paper, and means for lifting the rollers out of engagement with the paper 55 upon movement in one direction and to lower the rollers into contact with the paper upon movement in the opposite direction.

8. In a machine of the character described for affixing sheets of paper or the like to 60 mounts, a member over which the mounts are fed, a continuous conveying belt adapted to receive the sheets of paper, means for causing the belt to move forwardly for half the cycle of operation of the machine for 65 conveying the paper towards the mount, means for holding the belt stationary during the other half cycle of operation, and means for applying an adhesive to the paper while the belt is stationary. 70

9. In a machine of the character described for affixing sheets of paper or the like to mounts, a member over which the mounts are fed, means for feeding the sheets of paper through the machine and to be affixed 75 to the mount, a mounting roller for mounting the sheet of paper upon the mount, and means for holding the mounting rollers stationary during half a cycle of operation of the machine and to make a complete revolution during the other half cycle of operation. 80

10. In a machine of the character described for affixing sheets of paper or the like to mounts, a member over which the mounts are fed, means for supplying the 85 sheets of paper, means for applying adhesive to the sheets of paper, means for drying the adhesive, means for mounting the sheets of paper onto the mounts, and means for intermittently conveying the sheets of paper to the adhesive applying means, the drying means, and the mounting means. 90

11. In a machine of the character described for affixing sheets of paper or the like to mounts, a member over which the mounts are fed, means for supplying the 95 sheets of paper, means for applying adhesive to the sheets of paper, means for drying the adhesive, means for mounting the sheets of paper onto the mounts, and means for intermittently conveying the sheets of paper in a flat condition and in a horizontal plane to the adhesive applying means, the drying means, and the mounting means. 100

WILLIAM DOCKRAY RATCLIFF.
